WRECK FISHPLATE,
APPLICATION FILED OCT. 15, 1919.

Patented Feb. 15, 1921.

2 SHEETS—SHEET 2.

UNITED STATES PATENT OFFICE.

JOSEPH KEZON, OF SCARBORO, WEST VIRGINIA.

WRECK-FISHPLATE.

1,368,506.

Specification of Letters Patent. Patented Feb. 15, 1921.

Application filed October 15, 1919. Serial No. 330,743.

To all whom it may concern:

Be it known that I, JOSEPH KEZON, a citizen of the United States, residing at Scarboro, in the county of Fayette and State of 5 West Virginia, have invented a new and useful Wreck-Fishplate, of which the following is a specification.

It is the object of this invention to provide novel means whereby, through the instrumentality of fishplates on the rails of 10 a track, derailed rolling stock may be replaced readily upon the rails.

Another object of the invention is to provide novel means whereby the rails will be 15 prevented from spreading.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in top plan, a device constructed in accordance with the invention; Fig. 2 is a section taken approximately on the line 2—2 of Fig. 1; Fig. 3 is an end elevation showing one of the tie plates and parts carried thereby, the rail appearing in section; and Fig. 4 is a fragmental section taken longitudinally of one of the fishplates at the end thereof.

40 Since the device includes two structures which are practically alike, the description will proceed in the singular number.

In carrying out the invention there is provided a tie plate 1 equipped along its inner edge with an upstanding flange 2. The tie plates 1 are supported on ties 3 and are connected thereto by means of spikes 4. Fishplates 5 and 6 are mounted on the tie plate 1, the fishplate 5 being an outer fishplate 50 and the fishplate 6 being an inner fishplate. The fishplate 5 comprises a base 7 which is cut away as shown at 8 to receive the flange 9 of a track rail 10 including a web 11 and a ball 12. The base 7 of the fishplate 5 is 55 supplied with an upstanding flange 14 fitting against the web 11 of the rail 10 be-

tween the wall 12 and the flange 9 thereof, the central portion of the flange 14 lying in close relation to the ball 12 of the rail, as indicated at 150. From the ends of the portion 150 wings 15 slant outwardly, away from the rail 10. Those portions of the base 7 of the fishplate 5 lie between the wings 15 and the end portions of the flange 14 slants upwardly, as indicated at 14. The 65 base 7 of the fishplate 5 is held on the tie plate 1 by the spikes 4 and by bolts 16.

The fishplate 6 includes a base 18 through which certain of the spikes 4 and the bolts 16 pass, to hold the said fishplate on the tie 70 plate 1. The base 18 of the fishplate 6 is cut away as indicated at 19 to receive one side portion of the flange 9 of the rail 10. The base 18 of the fishplate 6 has an upstanding flange 20, coöoperating with the web 11 of the 75 corresponding track rail. The base 18 of the fishplate 6 is provided, further, with an upstanding flange 21, spaced from the ball 12 of the rail, to permit the passage of the wheel of the moving stock, there being a 80 groove between the parts 21 and 20, as indicated at 22. The flange 21 has laterally slanting wings 23. Between the wings 23 and the end portions of the flange 20 the base 18 of the fishplate 6 indicated at 24, slants 85 upwardly, like the part 17 of Fig. 4. Bolts 25 connect the upstanding portions of the fishplates 5 and 6 with the rails. If the fishplates are located at the joints, then there are, preferably four of these bolts, whereas, 90 if the fishplates are located between the joints, that is, intermediate the ends of the rails, then two of the bolts 25 will suffice. These details will be understood readily from an inspection of Fig. 1. 95

Connecting members 26 are provided, the same being recessed as shown at 27, to receive the fishplates 1 and the base portions 7 and 18 of the fishplates 5 and 6, the members 26 overhanging the base portions of the 100 fishplates, as disclosed best in Fig. 2, and as indicated by the numeral 28. Bolts 29 or other connecting devices pass through the bottom portions of the members 26, through the tie plates 1, through the bases 7 and 18 105 of the fishplates, and through the upper overhanging portions 28 of the members 26. The inner ends of the members 26 may be reduced, as shown at 30, and may be threaded to receive a loop 31, the parts 30 110 and 31 constituting, obviously a turnbuckle.

It will be clear that when a derailed car

approaches the fishplates 5 and 6, the wheel of the car, coöperating with the upwardly slanting surfaces 17 or 24, will be restored to the rails. The fishplates on the respective 5 rails, together with the tie plates 1 are united by the members 26 and the turn-buckle 30—31, and a spreading of the rails will be practically impossible.

Having thus described the invention, what 10 is claimed is:—

1. In a device of the class described, a rail; fishplates on opposite sides of the rail, each fishplate including a base having a longitudinal upstanding flange extended 15 along the rail, the flange being provided with terminal wings which slant laterally away from the rail, the base being supplied at its ends with upwardly sloping surfaces, located between the wings and the rail; se- 20 curing elements uniting the flanges of the fishplates with the rail; a tie plate whereon the bases of the fishplates are supported; a tie supporting the tie plate; and securing de-

vice passing through the bases of the fish- 25 plates and the tie plate and entering the tie.

2. In a device of the class described, a rail; fishplates on opposite sides of the rail, each fishplate including a base having a longitudinally upstanding flange extending along the rail, the flange being provided 30 with terminal wings which slant laterally away from the rail, the base being supplied at its ends with upwardly sloping surfaces, located between the wings and the rail; se- 35 curing elements uniting the flanges of the fishplates with the rail; a tie plate whereon the bases of the fishplates are supported; and a connector having recesses receiving the tie plate and the bases of the fishplates.

In testimony that I claim the foregoing as 40 my own, I have hereto affixed my signature in the presence of two witnesses.

JOSEPH KEZON.
